Inventor:
Harry C. Gowran
By G. A. Bragg Atty.

UNITED STATES PATENT OFFICE.

HARRY C. GOWRAN, OF TWO RIVERS, WISCONSIN, ASSIGNOR TO THE HAMILTON MANUFACTURING COMPANY, OF TWO RIVERS, WISCONSIN, A CORPORATION OF WISCONSIN.

DESIGN FOR A TABLE.

61,365.

Specification for Design.

Patented Aug. 15, 1922.

Application filed December 27, 1921. Serial No. 525,273. Term of patent 14 years.

To all whom it may concern:

Be it known that I, HARRY C. GOWRAN, a citizen of the United States, residing at Two Rivers, in the county of Manitowoc and State of Wisconsin, have invented a new, original, and ornamental Design for Tables, of which the following is a specification, reference being had to the accompanying drawing, forming part thereof.

In the drawing there is shown a perspective view of the table.

I claim:

The ornamental design for a table, as shown.

HARRY C. GOWRAN.
